(57) **CLAIM**

The ornamental design for an electric wine opener, as shown and described.

DESCRIPTION

FIG. 1 is a perspective view of an electric wine opener showing the new design.

FIG. 2 is a front view of the electric wine opener of FIG. 1. FIG. 3 is a rear view of the electric wine opener of FIG. 1. FIG. 4 is an enlarged view of the portion labeled with numeric 4 of the electric wine opener of FIG. 3.

FIG. 5 is a side view of the electric wine opener of FIG. 1. FIG. 6 is an opposite side view the electric wine opener of FIG. 1.

FIG. 7 is a top view the electric wine opener of FIG. 1; and, FIG. 8 is a bottom view the electric wine opener of FIG. 1. The dash-dash broken lines in the figures depict portions of the electric wine opener that form no part of the claimed design. The dash-dot-dash broken lines shown in FIGS. 3 and 4 are for the purpose of depicting the boundary lines of the enlarged view and form no part of the claimed design.

1 Claim, 8 Drawing Sheets
